UNITED STATES PATENT OFFICE.

HENRY KLECKLER, OF BUFFALO, NEW YORK, ASSIGNOR, BY MESNE ASSIGNMENTS, TO CURTISS AEROPLANE AND MOTOR CORPORATION, OF BUFFALO, NEW YORK, A CORPORATION OF NEW YORK.

AEROPLANE CONSTRUCTION.

1,290,838.

Specification of Letters Patent.

Patented Jan. 7, 1919.

Application filed January 13, 1916. Serial No. 71,892.

To all whom it may concern:

Be it known that I, HENRY KLECKLER, a citizen of the United States, residing at Buffalo, in the county of Erie and State of New York, have invented certain new and useful Improvements in Aeroplane Construction, of which the following is a specification.

My present invention relates to aeroplanes and contemplates more especially, improvements in the construction of aeroplanes of the type known as tractor biplanes. I consider it an object of prime importance comprehended by this invention to arrange a draft system for the aeroplane which shall conduct the tractor pull rearwardly through longerons terminating in transverse alignment with the bed of the motor and to tie respective wings, through the medium of their posts, and such additional rigid cross bracing as may be desirable, directly to common portions of the draft bearing longerons.

Other objects also specifically concerned with an aeroplane of the mentioned type relate in the production of novel means for hinging the lower set of wings of a biplane cell directly to the fuselage; in providing fittings of a special nature for the fuselage; in permitting the accommodation of a fuel tank adjacent the engine bed by avoidance of the normally interfering framework of the fuselage; by arranging operating and control means for the flight governing surfaces and by advancing a particular construction for the ground skid of the fuselage.

The above and additional objects, to be hereinafter more specifically treated, are accomplished by such means as are illustrated in the drawings, described in the following specification and then more clearly pointed out in the claims, which are appended hereto and form a part of this application.

With reference to the drawings, in which there is illustrated one embodiment of the invention, and throughout the several views of which like characters of reference designate similar parts,

Figure 1 is a side elevational view of the fuselage provided by the present invention, shown as stripped of its externals for the purpose of more clearly disclosing its construction;

Fig. 2 is a plan view of the same subject matter;

Fig. 3 is an enlarged side elevation of the engine section of the fuselage of the preceding figures showing the fuel tank in vertical section;

Fig. 4 is a plan view of the preceding enlarged figure, showing a horizontal section through the fuel tank;

Fig. 5 is a view in perspective of the engine plate;

Figs. 6 and 6^a are detail showings of the rudder foot bar disclosed in the assemblies of Figs. 3 and 4;

Figs. 7 and 8 are elevational details of the fuel tank *per se*.

Aeroplanes of the tractor type employed by the present invention usually carry their power plant forwardly in a fashion somewhat similar to the customary automobile practice, for direct driving of the tractor blade. The draft question, namely that of applying the tractive effort of the motor developed through the propeller pull in such manner as to avoid waste in the transmission of the power, involves the relation of the aerial supporting surfaces to the center of gravity of the machine in a fashion which will give a practical approximation of what may be termed the theoretical center of resistance, and also involves the connection of the axis of pull provided by the tractor screw to the center of resistance thus practically determined. These considerations are of major importance in determining a successful model of this type of aeroplane and such a draft question must be solved in the fabrication of the fuselage.

The present invention intends, accordingly, to provide a fuselage for an aeroplane of this type in which the practical determination of a theoretical center of resistance is provided and in which the motor and propeller mountings are such as to afford the best results in the connection of the axis of pull to this center. In addition, a system of draft wiring in supplementation of the usual lift and drift wiring has been provided.

The fuselage itself is mainly composed of a pair of upper longerons 25 and of lower longerons 26. The former are substantially horizontal in their normal extent from the tail post 27 forwardly to the fuselage engine section, beyond which they are bent downwardly in the manner denoted by the

numeral 28 for attachment to the engine plate 29. The lower longerons 26 are, however, curved in two directions simultaneously; vertically from the engine plate to the tail post and horizontally tapering from the maximum beam of the fuselage to the latter. Both the maximum width and the maximum depth of the fuselage is attained at and intermediately behind the engine section thereof, such engine section being defined by forward fuselage posts 30 and similar rearward posts 31. Parenthetically, it may be remarked that the term "engine section" is applied by custom to that part or portion of the fuselage to which the supporting surfaces are directly connected, owing to the old arrangement of suspending the motor also over the same portion of the fuselage. Although the position of the motor has since been changed the name has persisted as a designation of this particular fuselage section.

Continuing the fuselage posts 30 and 31 of the engine section, then, are the tapering wing posts 32 which are alined with the former posts by means of socket fittings 33 engaging the upper longerons. It is within this fuselage section that the theoretical center of resistance is to be approximated in practice. For all practical purposes it may be considered that the center of resistance is located in the horizontal plane of the upper longerons 25 within the engine section. Connection of the center thus approximated with the engine plate 29 is the next consideration and while a variety of ways suggest themselves, it is the object of this invention to provide this connection in the most simple and direct manner capable of accomplishing the objects sought. It is for this reason that the upper longerons 25 are continued directly to the engine plate 29, to which they are fastened in alinement with the forward extremities of the engine bed beams 34, ears 35 and 36 respectively secured to and angularly projected from the plate determining sockets for the beam and longeron extremities. The longeron extremities being thus arranged, reference being made particularly to Fig. 5, in direct lateral alinement with respect to the engine bed beams, it will be seen that the upper edge of the plate 29 serves as the most direct possible connection of the propeller pull to the defined center of resistance, through the curved portions 28 of the upper longerons, and that the intervention of any auxiliary draft members, as offered in some other types is wholly unnecessary. The propeller hub projects through the center of the plate as is provided for by the surrounding flange 35^a. Socket ears 36^a at the lower corner of the plate provide for the anchorage of the lower longerons 26. Lightening holes are arranged at proper intervals through the

plate and are each rimmed with a bent-up flange for strength.

Rearwardly, the engine bed beams are supported upon a cross bar 37 which is mortised into engine bed posts 38 vertically connecting corresponding upper and lower longerons, of the fuselage, immediately forward of the engine section. A draft bar 39 obliquely connects each fitting 33 of the forward fuselage posts 30 to the rear portion 75 of a wing panel 40 through the medium of the latter's supporting wing post 32. Wings (not shown) are hingedly attached to this panel which is of a width corresponding to that of the fuselage and also to the lower 80 extremities of the posts 30 and 31. Reaction stays 42 are employed to tie the upper wings both forwardly and rearwardly back to the fuselage.

It is understood that the specific construction of the fuselage includes the customary connection of longerons 25 and 26 by means of vertical struts 43 and horizontal struts 44, each of which is in turn cross connected by transverse bracing and by lift and drift 90 wiring 45. The fuselage framework is covered with a suitable substantially frictionless skin on the sides and bottom, while cowls 46 and 47 cover respectively the engine and the passenger sections, a rear cover 95 48 protecting the tail portion of the fuselage between the last named cowl and the fixed stabilizing surfaces. These latter are directly supported upon the upper longerons 25 and include the usual horizontal stabilizer 100 49 and the vertical fin 50. To the former are hinged the movable elevators 51 while upon the latter the rudder 52 is mounted, to provide the customary controlling surfaces.

The pilots' controls have been illustrated as of the Deperdussin type, including the aileron operating wheel 53 which is mounted within a fork 54 carried upon the lever 55, such lever being mounted for fore and aft oscillation upon its shaft 56 for actuation of the elevators 51 through the medium of the flexible connections 57 extending between each elevator and lever arms 58 carried at the extremities of the shaft 56. Through flexible connections 59 the rudder 52 may be 115 operated by movement of the foot lever 60 which is supported upon a short platform flooring within the pilots' cockpit. The observer or passenger is provided with a seat 61 within the engine section and in tandem 120 alinement with the pilots' seat 62 immediately therbehind, both of such seats being commonly supported by respective cross bars 63 upon the longitudinal bar 64.

The detail construction of the foot bar is 125 well illustrated in Figs. 6 and 6^a, in which the mounting base is denoted by the numeral 60^a, and serves to support a heavy projecting pin 61^a which is also rigidly maintained by a bearing sleeve 62^a intermediately sur- 130

rounding the pin and also carried upon the base 60^a. The bar 60 is mounted for movement upon the pin 61 and the sleeve 62^a in conjunction so that an efficient mounting is 5 provided which is at the same time of a simple nature. A V-shaped brace 63^a is secured as shown at 64^a to the mounting platform at the extremities of its spaced legs, the latter converging to anchor the exposed 10 upper end of the pin 61^a, some such means as the cotterpin illustrated being employed to maintain the whole for ready disassembly.

The positioning of the fuel tank in an aeroplane having its motor arranged far 15 forward is usually a matter of some difficulty, for while it is most desirable to place the fuel tank in immediate proximity to the engine, this is frequently interfered with by the fuselage framework in such manner 20 that the tank which could be introduced at the desired point would necessarily be much reduced in size. The present invention, however, solves this difficulty without loss 25 of a desirable position of the tank, and without reduction in the size thereof, by obviating any interference therewith of the adjacent fuselage framework. Referring now 30 to Figs. 3-6 inclusive, the fuel tank 65 has been positioned immediately in the rear of the engine bed 34, projecting back into the engine section. The strut 66 which connects 35 the upper extremities of the forward fuselage posts 30 is accommodated within a channel 67 formed entirely through the tank and rendered leak proof in any desirable 40 fashion. The tank is formed of some light metal which is provided with ribbing 68 and equipped with a gage float 69 of a customary character. A leak-tight recessing 45 cap 70 is also provided in the forward face of the tank to accommodate engine parts rearwardly projecting beyond the limits of the bed 34.

In Figs. 7 and 8 there is illustrated in detail 45 the method of supporting the tank, which does not devolve upon the strut 66 projecting therethrough. Flanges 71 are carried in lateral extension by the tank to overlie respective upper longerons 25 upon, 50 which they are supported through the medium of some cushioning means 71^a of felt or some similar partially elastic fiber material. From the engine bed beams 34 there depend the stirrup straps 72 which are connected by transverse strips 73 completing a 55 cradle for the support of the forward lower end of the tank. The cradle is also lined with the cushioning means 71^a which thus prevents transmission of the engine vibration directly to the tank contents, although detracting in no way from a superior 60 method of support.

Referring again to Figs. 1 and 2 of the drawings it will be noted that the engine 65 plate 29 functions not only as a rigid con-

nexion between the several longerons, (more particularly the lower) but also as a support for the radiator of the propelling power plant. The shape of the engine plate may be likened to the letter U. Its bight constitutes the connection between the lower longerons and its legs or extensions, the connection between the lower and upper longerons at opposite sides of the fuselage. Such interconnection between the longerons 75 together with the mounting of the radiator upon and forwardly of the engine plate constitutes the engine plate an integral part of the fuselage as well as an element of the utmost importance in fuselage design. 80

In conclusion, it may be noted that the running gear of the fuselage, while partaking of little individual novelty *per se*, has been arranged by this invention with particular regard to the draft system and to 85 the general fuselage arrangement. As will be remembered, the engine section as defined by the fuselage posts 31, comprehends a center of resistance in the plane of the upper longerons 25; the engine bed beams 90 34 determine an axis of pull which is connected directly to the fuselage engine section by means of the curved longeron portions 28 which serve to connect the engine plate 29 directly with the top of the posts 95 38, this plate and these posts forming the support for the engine bed, while these longeron portions are integral continuations of the longerons 25 in the plane of which a center of resistance is determined. The running gear posts or beams 133 then complete 100 the inter-relating of these particular fuselage elements by converging from the fuselage posts 31 and 38 to a common support of the axle 134 upon which the ground 105 wheels 135 are mounted for shock absorbing movement relative to the fuselage.

While in the foregoing, however, there has thus been illustrated in the drawings and described in the specification such combination 110 and arrangement of elements as constitute one preferred embodiment of this invention, it is desired to emphasize the fact that such departures from the particular embodiment disclosed may be made in later adaptations 115 of this invention as shall be recognized as within the scope of the appended claims.

What is claimed is:

1. In an aeroplane fuselage, longerons, an engine plate interconnecting the forward extremities of certain of said longerons, fuselage struts interconnecting upper and lower longerons at a point rearwardly removed from said engine plate, a cross strut connecting said fuselage struts, and engine bed beams terminally supported respectively by the engine plate and cross strut. 120

2. An aeroplane fuselage including longerons, an engine plate connecting corresponding extremities of the longerons, and 130

an engine bed supported at one end by said plate in transverse alinement with certain of said longerons.

3. An aeroplane fuselage including longerons, an engine plate connecting corresponding extremities of the longerons, posts intermediately connecting the corresponding upper and lower longerons, and an engine bed supported by said plate and said posts.

10 4. An aeroplane fuselage including longerons, fuselage posts connecting corresponding upper and lower longerons, an engine plate connecting extremities of the longerons, engine posts connecting said upper 15 and lower longerons between said plate and the fuselage posts, and an engine bed supported by the second mentioned posts and said plate.

5. An aeroplane fuselage including longerons, fuselage posts connecting corresponding upper and lower longerons, an engine plate connecting the extremities of the longerons, said longerons at their extremities converging from said posts, and engine 25 bed beams supported at one extremity by said plate in the vicinity of the bent extremities of said longerons.

6. An aeroplane fuselage including longerons, fuselage posts connecting corresponding upper and lower longerons, wing posts continuing the fuselage posts, means rigidly connecting opposite extremities of the wing posts, and an engine plate connecting extremities of said longerons in a vertical plane forwardly removed from the plane of said fuselage and wing posts.

7. An aeroplane fuselage including longerons, posts connecting upper and lower longerons, a plate connecting longeron extremities, an engine bed partially supported by said plate, posts connecting the longerons to further support said engine bed, and running gear beams secured to the second said posts and to certain of the first 45 said posts for convergence below the fuselage.

8. In an aeroplane, the combination with the longerons of the fuselage and the beams of the engine bed, of an engine plate, and 50 ears formed upon said plate to engage said longerons and said beams respectively.

9. In an aeroplane fuselage, the combination with a propelling power plant including in its ensemble a radiator, of longerons, and 55 an engine plate mounted at the forward extremity thereof dually functioning as an interconnection between said longerons and as a radiator support.

10. In an aeroplane, the combination with 60 the longerons of the fuselage and the beams of the engine bed, of an engine plate, transversely alined pairs of ears formed upon

said plate to engage the longerons, and transversely alined pairs of ears formed upon said plate and inwardly removed from the ends 65 thereof to engage said engine bed beams.

11. In an aeroplane, the combination with the lower longerons of the fuselage, of engine bed beams mounted at the forward extremity of the fuselage, and an engine plate 70 of substantially U-form having its extensions in engagement with the engine bed beams and its bight in engagement with said longerons.

12. In an aeroplane, the combination with 75 the longerons of the fuselage and the beams of the engine bed, of a skeleton plate provided with lightening holes, and ears formed upon said plate to engage said longerons and said beams respectively.

13. In an aeroplane, the combination with the longerons, of the fuselage and the beams of the engine bed, of a skeleton engine plate provided with lightening holes marginally flanged to increase strength, the terminal 85 portions of the plate being extended beyond the center portion thereof to provide an open space through which a portion of the engine may extend, ears formed upon said extended terminals to engage the engine bed beams, 90 and ears formed adjacent the bottom marginal edge of said plate to engage the longerons.

14. In an aeroplane, a fuselage framework, an engine bed contained within the 95 framework, straps dependent from said engine bed, means connecting said straps, and a fuel tank arranged within the framework in juxtaposition to said bed and partially supported by said straps.

15. An aeroplane including a fuselage framework, an engine bed contained within the framework, struts composing portions of the framework and a fuel tank mounted within the framework in juxtaposition with 105 said bed and provided with passage ways therethrough to accommodate elements projecting from said bed and struts forming part of said framework.

16. In an aeroplane fuselage, upper and 110 lower longerons, an engine plate connecting the forward extremities of the lower longerons at a point rearwardly removed from said engine plate, engine bed means supported at their forward extremity by the 115 engine plate, and means arranged between corresponding fuselage struts for supporting the engine bed beams at their rearward extremities.

In testimony whereof I affix my signature 120 in the presence of a witness.

HENRY KLECKLER.

Witness:

C. M. WEHRFRITZ.
